UNITED STATES PATENT OFFICE

2,505,438

MECHANICAL PENCIL

Ben J. Stoller, Green Bay, Wis.

Application November 5, 1948, Serial No. 58,399

5 Claims. (Cl. 120—18)

1

This invention relates to mechanical pencils, the primary object of the invention being to provide a mechanical pencil having means for projecting the lead beyond the writing end of the pencil by simply twisting the fingers which grip the pencil in writing, thereby eliminating the necessity of the person writing with the pencil, lifting the pencil from its writing position, in order to extend the lead, should the lead become broken or worn beyond use.

An important object of the invention is to provide a projecting and retracting mechanism for the lead of the pencil, the ejecting and retracting mechanism operating to rapidly eject or retract the lead.

Still another object of the invention is to provide an operating mechanism for ejecting the lead of the pencil which will, with each movement thereof, eject the lead a predetermined distance.

Still another object of the invention is to provide a mechanical pencil wherein the body portion or main barrel tapers towards the eraser end thereof to prevent slipping of the pencil through the fingers while the pencil is being used.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawing

Figure 1 is an elevational view of a mechanical pencil constructed in accordance with the invention, a portion of the operating band being broken away.

Fig. 2 is a longitudinal sectional view through the pencil.

Fig. 3 is a fragmental sectional view illustrating the position of the operating band and operating mechanism when the band has been moved to advance or extend the lead beyond the writing end of the barrel.

Fig. 4 is a sectional view taken on line 4—4 of Fig. 2.

Fig. 5 is a sectional view taken on line 5—5 of Fig. 2.

Fig. 6 is a sectional view taken on line 6—6 of Fig. 1.

Fig. 7 is a sectional view taken on line 7—7 of Fig. 6.

2

Fig. 8 is a sectional view taken on line 8—8 of Fig. 7.

Referring to the drawing in detail, the pencil comprises the body portion which is in the form of a barrel 5 having its writing end tapered as at 6, the major portion of the barrel also tapering from the tapered end 6 to the rubber supporting end 7 of the barrel, providing a surface which may be gripped without slipping, during the use of the pencil.

As clearly shown by Fig. 2 of the drawing, the body portion is formed with an inner tube 8 supported at one end by means of the end wall 9, while the opposite end of the tube 8 is supported by the partition 10, the inner tube 8 being spaced from the inner surface of the barrel 5, providing a compartment 11 for use in supporting refills or replacement lead sections not shown. Mounted within the inner tube 8 is the actuating sleeve 12 which is provided with the helical guide slot 13 which extends throughout the major portion of the length of the actuating sleeve, the lower end of the actuating sleeve terminating at a point adjacent to the extremity of the tapered end portion 6. At one end of the sleeve 12 is the knurled head 14 which is normally covered by means of the cap 15 that carries the rubber 16, the cap being readily removed from the end of the barrel 5 when it is desired to actuate the sleeve 12 for rapid rotation of the sleeve as when refilling the pencil.

Operating within the sleeve 12 is the tube 17 in which the lead is held, the tube 17 being provided with a pin 18 which is disposed within the helical guide slot 13 so that rotary movement of the actuating sleeve 12 will operate to feed the tube 17 and the lead held therein, longitudinally of the inner tube 8 to extend or retract the lead, according to the direction of rotation of the actuating sleeve 12. Secured to the actuating sleeve 12, at a point below the partition 10, is the ratchet pinion 19 which is engaged by the pawl 20 carried at one end of the bell crank lever 21 which is pivotally mounted on the bracket 22 that extends inwardly from the wall of the body portion or barrel 5, as clearly shown by Fig. 5 of the drawing.

Pivotally connected with one end of the bell crank lever 21 is a flexible wire 23 around which the spring 24 is coiled, one end of the spring 24 engaging the bell crank lever 21, while the opposite end thereof rests against the upper edge of the guide block 25 that extends inwardly from the wall of the barrel 5, the guide block having an opening through which the wire 23

operates. The wire 23 also connects with the lug 26 that extends into the barrel, the lug 26 being formed integral with the operating band 27 that is mounted for movement on the barrel 5. The barrel 5 is formed with an elongated circumferential opening 28 and an opening 29 communicating therewith at one end of the opening 28, through which the lug 26 extends. The opening 29 is disposed at right angles with respect to the opening 28, so that when the lug is moved through the opening 28, the operating band is rotated on the barrel, but when the lug 26 is moved into the opening 29, the operating band is moved longitudinally of the barrel. It will of course be seen that as the band 27 is moved longitudinally of the barrel, the wire 23 is pulled operating the bell crank lever 21 which in turn moves the pawl 20 rotating the pinion 19 and tube with which it is connected, in a direction to cause the tube 17 to be advanced, extending the lead which in the present showing is indicated by the reference character A, beyond the tapered writing end of the barrel.

The reference character 30 indicates a bracket which is supported within the barrel 5 at a point beyond the bracket 22, and this bracket 30 provides a support for the sliding pawl 31 which is provided with the rib 32 that moves in a slot formed in the bracket 30, there being provided a spring 33 disposed within the slot normally engaging the sliding pawl urging the sliding pawl to its inactive position, or the position as shown by Fig. 6 of the drawing.

The sliding pawl is designed to move to engage the ratchet pinion 34 as it moves to compress the spring, thereby rotating the actuating sleeve 12 to which the ratchet pinion 34 is connected, in the opposite direction, to retract the lead into the barrel to guard the lead against being broken while the pencil is carried in the pocket.

The lug 26 is provided with a notch 35 in one side thereof, which notch is adapted to accommodate the wire 23 directly above the head 36 of the wire 23 so that when the operating band 27 is moved longitudinally of the barrel, the wire 23 will be pulled. However, when the band 27 is rotated in the direction of the arrow as shown by Fig. 6 of the drawing, the lug 26 will disengage the wire.

The lug 26 is provided with an extension 37 that is adapted to engage the free end of the sliding pawl 31 to move the sliding pawl against the action of the coiled spring 33. When the band is released or returned to its normal position, it is obvious that the notch in the lug 26 will move to receive the wire 23 as shown by Fig. 6 of the drawing.

From the foregoing it will be seen that due to the construction shown and described, I have provided a mechanical pencil, wherein the lead may be advanced by merely pressing downwardly on the band 27, during the writing or use of the pencil.

When it is desired to retract the lead after writing, it is only necessary to rotate the band 27 which rotation operates the pawl 31 and ratchet pinion 34 moving the actuating sleeve 12 in the opposite direction to retract the lead.

Having thus described the invention, what is claimed is:

1. In a mechanical pencil, a barrel, an inner tube within the barrel, an actuating sleeve having a helical guide slot, mounted for rotation within the inner tube, a lead tube movable longitudinally within the actuating tube, a pin projecting from

said lead tube extending into the helical slot moving the lead tube and lead carried thereby longitudinally of the actuating sleeve as the sleeve is rotated, retracting and advancing the lead, an operating band mounted on the pencil providing a gripping surface when using the pencil in writing, and operating means operated by rotation of the band for rotating the actuating tube in one direction for retracting the lead tube and lead, and operating means operated by sliding movement of the operating band, rotating the actuating sleeve in the opposite direction for advancing the lead tube and lead beyond the writing end of the barrel.

2. In a mechanical pencil, a barrel, an inner tube mounted within the barrel, an actuating sleeve having a helical slot, mounted within the inner tube, a lead tube having a pin disposed within the slot, movable with the sleeve, spaced ratchet pinions secured to the actuating sleeve, an operating band mounted for longitudinal sliding movement and rotary movement on the barrel, a pivoted pawl operating means including a wire connecting the pivoted pawl and operating band whereby the actuating sleeve is rotated in one direction by rotation of the band, a pawl operating the opposite ratchet pinion and means connecting the band and latter pawl whereby sliding movement of the band, rotates the actuating sleeve in the opposite direction for moving the lead.

3. In a mechanical pencil, a barrel, an inner tube mounted within the barrel, an actuating sleeve having a helical slot, mounted for rotary movement within the inner tube, a lead tube slidably mounted within the actuating sleeve, spaced ratchet pinions having their teeth disposed in opposite directions, secured to the actuating sleeve, a pivoted pawl mounted within the barrel and engaging one of the ratchet pinions rotating the sleeve in one direction, a sliding pawl mounted within the barrel engageable with the other ratchet pinion for rotating the actuating sleeve in the opposite direction, an operating band mounted for rotary and sliding movement on the barrel, means connecting the operating band with the pivoted pawl and sliding pawl, whereby rotary movement of the band on the barrel operates the sliding pawl, and sliding movement along the barrel rotates the opposite ratchet pinion rotating the actuating sleeve in the opposite direction moving the lead tube and lead held therein.

4. In a mechanical pencil, a barrel, an inner tube mounted within the barrel, an actuating sleeve having a helical slot mounted for rotary movement within the inner tube, a lead tube slideable longitudinally within the actuating sleeve, a pin extending from the lead tube movable within the helical slot whereby said lead tube is moved longitudinally of the barrel as the actuating sleeve is rotated, a knurled head formed on the upper end of the actuating sleeve, whereby said actuating sleeve may be rotated for quick adjustment of the actuating sleeve, an operating band mounted on the barrel adjacent to the writing end of the barrel, means for transmitting rotary movement of the operating band to the actuating sleeve rotating the sleeve in one direction to retract the lead tube, and means for transmitting sliding movement of the band to the actuating sleeve, actuating the sleeve in the opposite direction advancing the lead tube.

5. In a mechanical pencil, a barrel, an inner tube mounted within the barrel, an actuating

sleeve having a helical slot, mounted for rotary movement within the inner tube, a lead tube slidably mounted within the actuating sleeve, a pin extending from the lead tube and disposed within the helical slot whereby rotary movement of the actuating sleeve moves the lead tube longitudinally of the actuating sleeve advancing or retracting the lead carried thereby, an operating band mounted on the barrel, said barrel having a circumferential elongated opening and having an elongated opening intersecting the circumferential opening at right angles with respect thereto, a lug extending from the operating band and disposed within the circumferential opening, a pivoted pawl disposed within the barrel, a ratchet pinion with which the pawl cooperates, a wire connecting the pawl with the lug whereby sliding movement of the operating band moves the pawl and ratchet pinion rotating the actu-

ating sleeve in one direction, a sliding pawl mounted within the barrel, a ratchet pinion spaced from the first mentioned ratchet pinion and secured to the actuating sleeve, said sliding pawl cooperating with the last mentioned ratchet pinion in rotating the actuating sleeve in the opposite direction, and an extension on the lug of the operating band movable into engagement with the sliding pawl operating the pawl as the operating band is rotated.
